TOOL FOR USE IN CONSTRUCTING MASONRY WALLS

Paul William Erickson, New York, N.Y.
(1930 Lacombe Ave., Bronx 72, N.Y.)
Filed May 21, 1962, Ser. No. 196,241
2 Claims. (Cl. 15—235.3)

This invention relates generally to implements or tools for use in constructing masonry walls.

It is an important object of the present invention to provide a building tool of the type described which enables even unskilled persons to build masonry walls of good workmanship and attractive appearance.

It is another object of the present invention to provide an implement or tool of the type described which is extremely easy to use, greatly simplifies and speeds masonry-wall construction, and substantially eliminates the need for skill in building masonry walls.

It is a more particular object of the present invention to provide a building tool or implement which is quickly and easily adapted to form a smooth layer of mortar on a wall under construction, and simultaneously to neatly form the sides of the mortar layer in a desired manner.

The present invention also contemplates the provision of a novel means for forming the mortar between the vertical brick surfaces to present an appearance conforming with that of the mortar between horizontal brick surfaces.

It is still another object of the present invention to provide a building implement or tool having the advantageous characteristics mentioned in the preceding paragraphs, which is extremely simple in construction, durable and reliable throughout a long useful life, and which can be economically manufactured for sale at a reasonable price.

Other objects of the present invention will become apparent upon reading the following specification and referring to the accompanying drawings, which form a material part of this disclosure.

The invention accordingly consists in the features of construction, combinations of elements, and arrangements of parts, which will be exemplified in the construction hereinafter described, and of which the scope will be indicated by the appended claims.

In the drawings:

FIG. 1 is a top perspective view showing a masonry wall under construction and illustrating a building tool of the present invention in its operative condition.

FIG. 2 is a transverse sectional view taken substantially along the line 2—2 of FIG. 1.

FIG. 3 is a longitudinal sectional elevational view taken substantially along the line 3—3 of FIG. 1.

FIG. 4 is a longitudinal elevational view showing an additional implement or tool of the present invention.

FIG. 5 is a generally horizontal view showing the tool of FIG. 4 and in operative association with a wall being constructed.

Referring now more particularly to the drawings, and specifically to FIGS. 1—3 thereof, a masonry wall is there generally designated 10 and shown in the process of being constructed. A tool, generally designated 11, of the present invention is shown in operative association with the upper region of the wall. Operating upon a lower region of the wall, see FIG. 1, is illustrated a tool or implement 12 of the present invention, which is shown in greater detail in FIGS. 4 and 5.

As illustrated, the wall 10 is of a two-layer construction, having bricks 15 arranged in a pair of vertical, side-by-side inner and outer layers, as best seen in FIG. 2. The bricks 15 of wall 10 are also arranged in horizontal layers, as well as vertical layers, the horizontal layers

2

being separated by interposed mortar layers 16, and the vertical layers being separated by an interposed vertical layer of mortar 17. Of course, the instant invention is adapted for use with a wide variety of masonry-wall constructions, the particular construction shown herein being only by way of illustration and without limiting intent.

It will also be observed in FIG. 2 that the wall 10 seats upon a footing 18, which may be embedded in the ground 19.

10 The building tool or implement 11 includes a generally rectangular, substantially flat member or plate 21 of a width approximately equal to the thickness of the wall 10 being constructed. The plate 21 has one end edge 22 extending laterally or transversely between opposite side edges of the plate, substantially normal thereto. Along the side edges of the generally rectangular member or plate 21 there may be provided upstanding lips or flanges 23; and, a rear wall 24 may upstand from the rear end of the plate opposite to the end edge 22. The rear wall 24 may be of greater height than the side flanges or lips 23, and may be provided on its side edges with forwardly extending lips or flanges 25, each substantially coplanar with a respective adjacent flange 23.

The plate member 21 is further provided with a protuberance 27 on its underside, spaced medially between the side edges of the member. As illustrated, the depending protuberance 27 may extend longitudinally of the plate 21 and be formed thereon by a longitudinally extending, medially located, upwardly facing depressed region 28.

Extending longitudinally along each side of the plate 21 is an elongate platelike side member 30. More specifically each side member 30 extends longitudinally along a respective side of the plate 21. Substantially normal thereto, and may have its upper region extending above the plate 21 and secured by welding or other suitable means in facing engagement with the outer surface of the adjacent flange or lip 23. The lower region of each side member 30 depends generally vertically below the plate 21 and terminates in a generally horizontal lower edge 31. The side members or plates 30 may extend longitudinally beyond the plate 21, each having its forward region terminating beyond the forward plate edge 22 in an upwardly obliquely inclined edge 32, and extending 45 rearwardly beyond the rear end of plate 21 to provide a trailing portion 33.

As seen in FIGS. 1 and 2, an upper layer 35 of mortar is spread on the upper course of bricks 15, and the tool 11 arranged with the plate 21 superposed over the wall 50 and the side members 30 depending along opposite sides of the wall. In this condition, the tool 11 is movable longitudinally along the wall, as will appear in greater detail hereinafter.

In order to properly space the plate 21 above the upper course of bricks 15, and leave therebetween an upper mortar layer 35 of proper thickness, there are provided internally of the side members 30 spacer means 37 engageable with the upper course of bricks. The spacer means 37 may each consist of an internal protrusion or bead 60 extending longitudinally along and on the inner side of a respective side member 30 adapted to ride on the adjacent upper corner of the upper course of bricks. The underside of each bead or rib 37 is properly spaced below the underside of the plate 21 a distance equal to the desired thickness of finished layer 35, as seen on the right-hand sides of FIGS. 1 and 3; and, the spacer beads 37 are spaced above the lower side-member edges 31 such that the lower regions of the side members are engageable with opposite sides of the wall 10 to guide the tool 11 longitudinally along the wall.

As best seen in FIG. 3, upon longitudinal movement of the tool 11 along the wall 12 in the direction of arrow 39,

the leading edge 22 of the plate 21 cuts through the layer 25 to remove a portion thereof greater than the desired thickness and receives the removed portion on the upper side of the plate 21.

In order to facilitate operation, a forward handle 40 may be provided on the tool 11 by a pair of upstanding extensions 41 from the forward regions of flanges 23, and a hand grip member 42 extending between and secured to the upper ends of the extensions in spaced bridging relation with respect to the plate 21. Similarly, a rear handle 43 may be provided on the rearward end portions 33 of the sidepieces 30 by a pair of arms 44 each pivoted at one end, by pins 45 to the side members and having their other ends connected by a hand grip 46.

The handles 40 and 43 may then be conveniently employed to move the tool 11 along the wall 10 for removing excess mortar from the layer 35 onto the plate 21, to leave the upper mortar layer of proper thickness or height and having well-defined sides as formed by the spacer beads 37. Of course, the mortar removed to the upper side of plate 21 may be reused to effect substantially economy of materials. Further, in the illustrated embodiment the depending protuberance 27 formed in the plate 21 by the depression 28 serves to compact mortar into the vertical mortar layer 17 between the vertical layers of brick.

In addition, the tool 12 is best seen in FIGS. 4 and 5 as including an elongate handle 50 having secured at one end an outwardly facing, generally U-shaped journal bearing 51. The journal bearing or support 51 has its bight region fixed to the handle 50 by any suitable fastener means 52, and has its legs 53 extending in facing spaced relation generally away from the handle. Journaled between the legs 53 is a rotary member or wheel 54, which is freely rotatable about a central axis extending between the legs 53. The peripheral configuration of the wheel 54, as best seen in FIG. 5, may be of a central convex curvature 55 which merges at each side with an outer concave curvature 56. The tool 12 is particularly well adapted for use as illustrated in FIGS. 1 and 5, by rolling engagement of the periphery of wheel 54 with the mortar between bricks 15, and especially between the vertical surfaces of adjacent bricks. By this means, the exposed mortar surfaces are properly finished, and the mortar surfaces along horizontal and vertical layers of mortar may be finished in conformity with each other, in accordance with the similar configuration of the beads 37 and periphery of wheel 54.

In addition to the operation of tool 11 described hereinbefore, the tool may also be used in similar manner to form the footing 18. If desired, a level may be applied to the tool 11 to maintain the same horizontal, especially in formation of a footing 18, but also in the first-described manner of usage.

From the foregoing, it is seen that the present inven-

tion provides improvements in building implements for masonry walls and the like, which fully accomplish their intended objects and are well adapted to meet practical conditions of manufacture and use.

Although the present invention has been described in some detail by way of illustration and example for purposes of clarity of understanding, it is understood that certain changes and modifications may be made within the spirit of the invention and scope of the appended claims.

Having thus described my invention, what I claim as new and desire to secure by Letters Patent is:

1. A building tool for use in masonry construction comprising a generally flat plate of a width approximately equal to the thickness of a masonry wall and having a laterally extending leading end edge, said plate being adapted for superposition over a wall during construction, depending side members on opposite sides of said plate engageable with opposite sides of the wall for guiding the plate along the wall, and spacer means on the inner sides of said side members spaced a predetermined distance below said plate and adapted to ride on the wall to maintain said plate in spaced relation over the wall, whereby said leading plate edge is adapted to cut a layer of mortar on the wall to leave a predetermined thickness of layer on the wall and remove the remainder to the plate, said plate being of a width slightly greater than the width of two bricks for use on a two-layer brick wall, and said plate having a depending protuberance medially between said side members for depressing mortar between the brick layers, said spacer means comprising internal protuberances on said depending side walls configured to form the sides of the remaining mortar, and said internal protuberances comprising elongate beads extending longitudinally of said depending side walls spaced between said plates and the lower edges of said depending side walls.

2. A building tool according to claim 1, in combination with a handle connected to and bridging said plate for manually moving the plate along the wall and passing therebelow the removed mortar, and upstanding walls along opposite sides and the other end of said plate for retaining said removed mortar.
